US00D990506S

(12) **United States Design Patent** (10) Patent No.: **US D990,506 S**
White et al. (45) Date of Patent: **** Jun. 27, 2023**

(54) **DISPLAY SCREEN WITH GRAPHICAL USER INTERFACE**

(71) Applicant: **Bottomline Technologies Limited**, Reading (GB)

(72) Inventors: **Kellie White**, Abingdon (GB); **Martin Weller**, Reading (GB)

(73) Assignee: **Bottomline Technologies Limited**, Reading (GB)

(**) Term: **15 Years**

(21) Appl. No.: **29/838,947**

(22) Filed: **May 17, 2022**

Related U.S. Application Data

(63) Continuation of application No. 29/711,444, filed on Oct. 31, 2019, now Pat. No. Des. 954,070.

(57) **CLAIM**

The ornamental design for a display screen with graphical user interface, as shown and described.

DESCRIPTION

FIG. 1 is a front view of a first embodiment of a display screen with graphical user interface; and, FIG. 2 is a front view of a second embodiment of a display screen with graphical user interface.

The present invention relates to a display screen with graphical user interface. The outermost broken lines represent a display screen and form no part of the claimed design. The remaining broken lines illustrate portions of the graphical user interface that form no part of the claimed design.
